COMBINATION TOOL

Herman Folkers, Omaha, Nebr.

Application October 8, 1942, Serial No. 461,311

2 Claims. (Cl. 30—252)

This invention relates to a combination tool.

An object of this invention is to provide a combination tool including a claw hammer, cutter, wrench, square and measuring device.

Another object of this invention is to provide a tool of this kind including a pair of pivoted handles, and means for normally holding the handles in spaced relation so as to provide a resilient grip, the holding means being so constructed as to provide one side of a square in addition to maintaining the handles normally apart.

A further object of this invention is to provide, in a hammer formed of a pair of pivoted handles having respectively a claw and driving head secured thereto, means on opposite sides of the pivot for the handles to provide a firm structure to permit driving or pulling of nails or the like.

The invention consists of the new and useful construction, combination and arrangement of parts as herein described and claimed, and as shown in the accompanying drawing, it being understood that changes, variations and modifications may be resorted to which fall within the scope of the invention, as claimed.

In the drawing:

Figure 1 is a detail side elevation, partly broken away, of a tool constructed according to an embodiment of this invention;

Figure 2 is a sectional view taken on the line 2—2 of Figure 1;

Figure 3 is a fragmentary side elevation of the tool used as a square and rule;

Figure 4 is a fragmentary end elevation of the outer end of the device, showing the use of the device as a cutter;

Figure 5 is a view, similar to Figure 4, but showing the cutting blades in overlapping position; and

Figure 6 is a fragmentary side elevation of the device used as a square.

Referring to the drawing the numerals 7 and 8 indicate a pair of elongated handles which are provided with cover members 9. The cover members 9 engage about three sides of the handle members 7 and 8, as shown in Figure 2, the handle members 7 and 8 being generally of rectangular configuration in transverse section. The handle members 7 and 8 are pivotally secured together by a pivot bolt 10 and the handle 7, at its forward or outer portion, is formed with an obtusely disposed flattened extension 27 which merges into a striking head 13. The handle member 8 is also flattened, as at 28, and this flattened portion extends obtusely to the length of

the handle 8 and overlaps the flattened portion 27 of the handle 7.

The outer or forward end portion of the extension 28, has formed integral therewith, a claw 14 which is of conventional construction, and provides a means for pulling nails or the like. The extension 28 has also formed integral therewith, an acutely disposed jaw 11 and the extension 27 also has formed integral therewith, and disposed at an acute angle to the extension 27, a complementary jaw 12. The jaw 11 has formed integral with the free end thereof, a cutter blade 19, which is offset to one side of the jaw 11, thereby providing an abutment 21.

15 The jaw 12 has formed integral therewith a complementary cutting jaw 19' which is offset from the side of the jaw 12, opposite from the cutting member 19, so that when the two jaws 11 and 12 are moved toward each other the cutting members 19 and 19' will be disposed in overlapping position.

15 The jaw 12 is formed with an abutment 21' against which the adjacent free end of the cutting member 19 is adapted to engage when the 25 two cutting members 19 and 19' are in the position shown in Figure 5. The cutting member 19 is formed with a flat inner face 20, and the cutting member 19' is formed with a flat inner face 20' and these two flat faces 20 and 20' are disposed in confronting position when the jaw members 11 and 12 are closed. When the jaw members 11 and 12 are open a space 18 is formed between the abutment 21 and the adjacent or free end of the cutting member 19' and at the 35 same time a space 18' is formed between the free end of the cutting member 19 and the abutment 21'.

In order to provide a means whereby the two handles 7 and 8 may be held in spaced parallel 40 relation to each other when the jaws 11 and 12 are closed, I have provided a right angularly disposed plate 17 which is secured, as by welding or the like, to the handle 17 inwardly or rearwardly of the pivot member 10 and adjacent the outer end of the cover 9 carried by the handle 7.

45 The plate 17 forms one side of a square and this plate extends on opposite sides of the handle 7 so as to thereby form a stop member 24 which extends inwardly from the handle 7 and is adapted to contact with the handle 8. A second projection 29 extends in overlapping position with 50 respect to the handle 8, and provides an additional length to the plate 17 for firmly holding the handle 7 at a right angle to the plate 17 when the latter abuts against an edge of a piece

of work. By providing the stop member 24 for holding the two handles 7 and 8 in spaced parallel relation, a resilient hand grip will be provided for the tool when it is used as a hammer.

The handle 7 on the inner side thereof, has secured thereto a rule 15 which is secured to the handle 7 by fastening members 16. The handle 8 also has secured to the inner side thereof a second rule 15' similar to the rule 15. The rule 15 is adapted to be used after the manner shown in Figure 3 and with the two handles 7 and 8 in a sufficiently open position to expose the rule 15. In Figure 3 the handle 7 is disposed on the upper side of a piece of work e, and engages against the adjacent end d. In this manner the rule 15 can be used to determine any marking or cutting which might be desired with respect to the piece of work e.

In Figure 6 the tool is also used as a square with the plate 17 abutting against the side a of a piece of work. The piece of work may be marked along the straight edge formed by the rule 15 so as to permit cutting of the outer portion c of the work b.

Where the tool is used for cutting a piece of metal or the like, the handles 7 and 8 are moved to an open position, as shown in Figure 3, and a work piece 22 is inserted between the two cutting members 19 and 19'. The handles 7 and 8 may then be moved toward each other so as to cause the cutting members 19 and 19', to move to the closed position as shown in Figure 5.

In order to provide a means whereby the tool may be used after the manner of a wrench for turning either a nut or a pipe, the inner sides of the handles 7 and 8, outwardly from the plate 17, are formed with a pair of arcuately disposed series of serrations 25 and 26. These serrations will hold the nut or other article which may be disposed between the two handles 7 and 8.

By providing a tool, as hereinbefore described, with a pair of pivoted handles, and forming the

article cutting jaws on the outer ends of the handles in such a manner that the cutting jaws overlap and abut each other, as shown in Figure 5, the tool will be a firm tool when used as a hammer, as where a nail is being driven by the head 13 or a nail or other article is being pulled by the claw 14.

This tool will provide a combination tool structure for use by a carpenter, mechanic or the like, and will eliminate the necessity of having separate tools to perform a series of simple operations.

I claim:

1. A tool comprising a pair of elongated handles, means pivotally securing said handles together, a pair of confronting jaw members carried by said handles outwardly of said pivot means, and overlapping cutters carried by said jaw members, each jaw member including an abutment at the inner end of its cutter and offset from the latter for engagement with the terminal end of the other cutter to thereby provide substantially flush inner and outer surfaces on said jaw members, said abutment being disposed at right angles to the adjacent face of a cutter.

2. In a tool of the class described, a pair of elongated handles pivotally secured together by a pivot bolt, and each having an extension, each extension having a part disposed at an acute angle thereto providing a jaw, the two jaws being complementary to each other, each jaw having formed integrally with the free end thereof a cutter blade, the said blades being each oppositely offset from the respective jaw, each jaw having an abutment provided by the said offsetting of its blade, each blade having a flat inner face, the said faces being disposed in confronting position when the jaws are closed and the cutting edges of the respective blades underlie one another.

HERMAN FOLKERS.
